UNITED STATES PATENT OFFICE.

ALFRED H. COWLES, OF CLEVELAND, OHIO.

ELECTRIC FURNACE AND METHOD OF OPERATING THE SAME.

SPECIFICATION forming part of Letters Patent No. 335,058, dated January 26, 1886.

Application filed May 15, 1885. Serial No. 165,583. (No model.)

To all whom it may concern:

Be it known that I, ALFRED H. COWLES, a citizen of the United States, residing at Cleveland, in the county of Cuyahoga and State of Ohio, have invented certain new and useful Improvements in Electric Furnaces and Method of Operating the Same; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to electrical smelting furnaces operating on the incandescent principle, in which metallurgical operations requiring an intense heat are carried on, with electricity as the heat-producing agent.

This invention consists in the improved method of operating incandescent electric furnaces herein described, and in the combination, with a furnace containing a charge of electrical resistance material, of two movable electrodes situated at opposite ends of the furnace, and projecting into the body of the charge contained within it, so that the said electrodes may, when the resistance runs down, be drawn apart, thereby increasing the amount of the charge between the electrodes, and consequently increasing the resistance, and thus preserving a uniform resistance within the furnace.

The invention also consists in the arrangement of suitable mechanism actuated by the current or a portion of the same for automatically moving the electrodes, so as to govern the amount of energy utilized in the furnace.

Figure I in the drawings represents a longitudinal section of the furnace. Fig. II shows substantially the same view of the furnace, and shows also the arrangement of mechanism for automatically drawing apart the electrodes by means of a magnet, vibrating armature, and shunt circuit; also shows the construction of the contact boxes employed.

Are the furnace-walls, which may be constructed of fire-brick or other similar material. They are preferably constructed so that the furnace has its largest dimensions in a horizontal direction, and is comparatively shallow

in depth, as this form of construction is found to be best adapted for the free escape of the gases evolved from the charge during the process of reduction.

B is a lining for protecting the walls of the furnace. This lining is formed of finely-pulverized charcoal or other similar material of inferior electrical conductivity to the charge to be operated on, and which is also a bad conductor of heat.

C is the positive, and C' the negative, electrode. Connected to these are the wires c and c', for conducting the electricity to the furnace. These electrodes are preferably formed of rods of carbon, which project into the body of the charge through the furnace walls and lining.

D is the charge. This consists, ordinarily, of electrical resistance material—such as electric-light carbon—and the ore to be reduced. Both of these are previously pulverized and intimately mixed together before being placed in the furnace; but in some cases pulverized ore alone is used when it is a sufficient conductor of electricity. The charge fills the whole length, with the exception of the protecting-packing B at the ends of the furnace, and it presses against the sides and ends of each of the electrodes which project into it. The current of electricity flows from the sides and ends of the said electrodes through the charge, and causes the electrical resistance material in the charge to become incandescent. The intense heat of the said incandescent material reduces the ore.

When the furnace is employed for the reduction of ore, the metal is found at the close of the operation filling the interstices between the particles of carbon, mixed with it, and at the bottom of the furnace, where it collects upon the charcoal floor after having worked down through the charge. When the furnace is started, the electrodes are near together in the positions indicated by dotted lines the resistance at the start being very great. After the furnace has been running for a while, and this portion of the charge between the electrodes has become heated, the resistance falls, and the electrodes are then drawn out a little, increasing the length of the charge between them, and bringing into the active part of the electrical field additional parts of the charge.

In this manner by successive withdrawals of the electrodes a uniform resistance is preserved until the entire charge is brought into action.

5 The movement of the electrodes may be effected by clock-work mechanism, by hand, or automatically by the current of electricity in the circuit, so that the greatest possible amount of electrical energy in the circuit may be utilized from the beginning to the end of the operation in the furnace.

10 In Fig. 2 is shown a convenient manner of operating the electrodes automatically by means of a shunt-circuit, magnet, and vibrating armature.

15 G represent magnets connected in the main circuit, and wound in the opposite direction with the wire of the shunt-circuit. That from the positive pole leads to the positive electrode C, and that of the negative pole leading to the contact-point g.

H is a vibrating armature, with a contact-point, h, connected by a wire leading to the negative electrode C', or to the main wire leading thereto. To the armature is attached the spring I; the tension of which is regulated by the key i.

J is the rod by which the armature is suspended, and at the upper end is provided with 20 a friction-clutch, j, embracing the hub of the ratchet-wheel K, the teeth of which are engaged by the retaining-pawl k. A train of gears connect the ratchet-wheel with the gear L, that engages the rack M, that is attached 25 to the electrode C'. This rack also engages the pinion N, that is connected by a cross-belt or other suitable means with the duplicate pinion, N', engaging the rack M', connected with the electrode C, by which arrangement the 30 electrodes are simultaneously moved equal distances in opposite directions.

The electrodes are employed not alone to maintain a given resistance, but also to throw fresh ore into the zone of reduction.

35 In operating the furnace, as the heat increases and the electrical resistance consequently decreases, causing too great a current, the armature H is drawn toward the magnet, causing a contact of the points g and h, connecting the shunt-circuit, by means of which a portion of the current is passed around instead of through the furnace, thus lessening the power of the magnet, so that the armature is again drawn to its normal position by the 40 tension of the spring.

45 With the movement of the armature toward the magnet the friction-clutch slides on the hub of the ratchet-wheel; but with the reverse movement of the armature, caused by the spring, the ratchet-wheel 50 is advanced a notch, thereby withdrawing the electrodes a trifle from the furnace, and such increase in the distance between the electrodes of course increases the electrical resistance, and consequently decreases the volume of electrical current through the furnace. As the 55 electrodes are drawn apart by successive increments, additional portions of the charge

drop into the spaces in front of the electrodes, and a continuous body of material is preserved between them and in contact always with both. The extent of this mass of material within the zone of action gradually increases until the whole of the charge is involved.

Of course various modifications of the governing mechanism may be made without departing from the spirit of my invention.

10 In charging the furnace the pawl may be thrown back and the ratchet-wheel turned by hand to adjust the electrodes. If the electrodes in the heated condition in which they usually emerge from the furnace were exposed to the air, they would oxidize and be reduced in size, to avoid which I have provided the copper contact-boxes P, that are secured to the walls A, and have lateral holes through which the electrodes pass. The boxes are filled with, preferably, coppershot, R, of small size, surrounding the electrodes. Copper, on account of its well-known properties of conducting heat and electricity, is preferable in most cases for this purpose, and the wires are attached to the boxes P.

15 As the heated portions of the electrodes emerge slowly from the furnace, they first encounter the shot, by means of which the heat is rapidly transmitted from the electrodes, so that the heated portions, as they pass out of the respective boxes, are so much reduced in temperature that they are not injured by exposure to the air. The shot or globular form for the packing or filling in the box P is not essential, but is preferable. The movement may be confined to but one of the electrodes, or both may be made movable. It will be seen that the feed mechanism of an arc light may be readily adapted to move the electrodes outward as the resistance falls; but in the present case such a feed mechanism, instead of being adjusted so as to maintain the extremities of the electrodes at a uniform distance apart and to feed them in toward each other as they are consumed, is so arranged that it feeds the electrodes outward farther and farther apart as the operation progresses, the space between them always being kept filled with the charge. If it were desired to lessen the resistance during the smelting operation, by lessening the amount of the charge between the electrodes, they may be pushed in; and in order to allow this they should be made with pointed ends.

20 E is a layer of granular charcoal covering the top of the charge.

F is a slab of fire-clay, or other similar material, provided with vent-holes f. This slab covers the whole of the top of the furnace, and is luted around the edges before the operation commences. A small space is left between the top of the layer of charcoal, E, and the bottom of the slab F. The gases given off by the charge during the process of reduction pass off through the layer of granular charcoal and out of the vent-holes f.

25 I am aware that it is not new to make the electrodes of an electric furnace automatically adjustable, so that as the resistance diminishes

they are drawn apart, and I do not claim the same, broadly; but all such attempts and experiments have relation to furnaces in which the electric arc is employed, and the electrodes being subject to rapid wear the loss must be compensated for. The conditions there existing are similar to those found in the case of an electric-arc light—a constant distance must be preserved between the electrodes, and the wear thereof must be compensated for; but in the present instance there is no material wear to the electrodes, a continuous body of material is preserved between the electrodes, and the distance between them varies, gradually widening from the beginning of the operation until the whole of the charge is brought into action.

Having thus fully described my invention, what I claim as new, and desire to secure by Letters Patent, is—

1. The method of smelting ores and other substances by the incandescence of an electrical resistance material contained in said substances or mixed therewith, which consists in first bringing a limited quantity of the material to be treated between a pair of electrodes, and then gradually increasing the quantity of such material by causing the electrodes to recede from each other, substantially as herein set forth.
2. In the art of smelting ores and other substances by the direct heating action of the electric current, the method of obtaining a uniform action of said electric current upon the mass or charge to be treated, herein described, which consists in introducing into the charge electrodes which are normally in proximity to each other, and then gradually causing said electrodes to recede from each other, the contact with the charge still being preserved until the mass of the charge is contained between the said electrodes, substantially as set forth.

3. In an incandescent electrical smelting apparatus, the combination of a furnace-chamber having electrodes fitted into its opposite sides, with suitable mechanism for bringing said electrodes normally in proximity to each other within the furnace-chamber and gradually separating the same during the smelting process to the full extent of said furnace-chamber, substantially as herein set forth. 50

4. In an incandescent electrical smelting apparatus, the combination of a furnace-chamber having electrodes fitted into its opposite sides, mechanism for normally bringing said electrodes in proximity to each other and gradually separating the same during the smelting process to the full extent of the furnace-chamber, and a charge of electrical resistance material in contact with both electrodes during the entire process, substantially as herein set forth. 55

5. The combination, with an adjustable electrode of an electric furnace, of a mass of heat-conducting particles, preferably globular, encompassing the electrode outside of the furnace-chamber, substantially as and for the purpose set forth. 65

6. The combination, with adjustable electrodes, of contact-boxes, preferably of copper, located one at either end of an electric furnace, 70 and through which the electrodes pass, filling for the boxes, preferably of copper, and preferably of a globular formation, arranged around the respective electrodes and in contact therewith, substantially as set forth. 75

In testimony whereof I affix my signature in presence of two witnesses.

ALFRED H. COWLES.
